2,051,151

AERONAUTICAL TOY

John K. Northrop, Los Angeles, Calif., assignor
to Northill Co. Inc., Los Angeles, Calif., a cor-
poration of California

Application July 16, 1935, Serial No. 31,601

4 Claims. (Cl. 46—83)

My invention relates to an aeronautical toy, and more particularly to a miniature helicopter and means for causing the device to rise in the air.

5 Among the objects of my invention are: To provide an aeronautical toy capable of a rising flight; to provide such a toy together with means for increasing the time of descent; to provide a miniature helicopter equipped with a parachute; 10 to provide such a helicopter wherein a parachute is released at or near the apex of its flight; to provide a toy helicopter designed on modern aeronautical principles; to provide a toy helicopter carrying a parachute which is released 15 at a predetermined point in its flight by the action of centrifugal force; to provide a toy helicopter with parachute releasing means under the control of a governor operated by the speed of rotation of the helicopter; to provide, in a 20 helicopter carrying a releasable parachute, means for damping rotation of the propeller thereof upon release of the parachute; to provide a helicopter and driving means cooperating to control a centrifugal governor before release from the driving means; to provide a simple and efficient 25 aeronautical toy; and to provide an improved impulse driven helicopter.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not 30 limit myself, in any way, to the apparatus of the present application, as I may adopt various other apparatus embodiments, utilizing the method, within the scope of the appended claims.

Referring to the drawing:

40 Figure 1 is a longitudinal view in elevation of a preferred embodiment of my invention.

Figure 2 is a top plan view of the device illustrated in Figure 1.

Figure 3 is a side view in elevation of my invention after release of the parachute.

Figure 4 is a sectional view taken as indicated by the line 4—4 in Figure 2.

Figure 5 is a sectional view taken as indicated by the line 5—5 in Figure 2.

50 Figure 6 is a perspective detail view partly in section of the governor arm mounting.

In general, my present invention resembles prior apparatus wherein a propeller is rotated by hand or otherwise until sufficient speed of rotation is obtained for the rotor to develop lift and

rise into the air leaving the driving means behind, and climb until such time as the speed of rotation fails to sustain the propeller any longer, whereupon the propeller falls and returns to the ground. I have termed such propeller for the purpose of this application a helicopter although no attempt is made for the propeller to carry any power plant, the power being purely rotational force stored in the propeller by an initial 5 rotational impulse.

My device, however, differs from the prior art in that I have provided a centrifugally operated governor which may be adjusted to release a 10 parachute from the propeller assembly adjacent the apex of its flight but preferably shortly after 15 the propeller has started to descend. In this way, the descent is delayed and a longer time of flight can be obtained.

Furthermore, I have designed my helicopter with all due regard to modern aeronautical practice so that not only can maximum power be 20 stored in the rotor, but also maximum altitude can be obtained during the release of that power. To this end, the propeller blades are provided with contours which have been found to be the 25 most efficient for climbing, and a rim has been provided having minimum air resistance, for power storage.

Other broad aspects of my invention may be more readily understood by direct reference to 30 the drawing. A circular disc, preferably of a light strong material, such as one of the aeronautical aluminum alloys, is radially cut out to provide, preferably four, propeller blades 1 with connected tips, these blades being given at the 35 same time a calculated propeller curvature as shown in the sectional views in the drawing. The cuts preferably do not extend to the axis of the disc but a central portion is left which is dished downwardly to provide a central cup 2. I also 40 prefer to turn the periphery of the disc to form a dished edge 3 for strength, peripheral weight, and stability, this edge also re-enforcing the propeller blade tips against landing shocks.

A cover 4, preferably cup-shaped, is provided, 45 having the same general diameter as the cup 2 and is preferably hinged to the propeller body by means of a pin 5 passing through lugs 6 which are turned to form a pin bearing, and a cup lug 7 which is preferably stamped integral with the 50 disc and turned to receive the pin 5. The pin 5 is then passed through all three lugs, and in case the pin is a cotter key, the ends bend outwardly; or in case of a solid pin, the end is burred to maintain the pin in place.

Directly opposite the hinge a locking lip 8 is provided on the edge of the cover, and a governor bar 9 extending downwardly, passes through a slot 10 in a governor lug 10' and is maintained therein by punch 11 below the propeller and by a locking lug 12 above the propeller, the locking lug 12 being so situated that it will engage the locking lip 8 on the cover and maintain the cover closed when the lower end of the governor bar 10 is subjected to a force tending to move it outwardly. A hinge spring 14 is provided, which will open the cover by breaking the engagement of the locking lug 12 and the locking lip 8 when no force is applied to the lower end of the governor bar.

The propeller is also provided, on a diameter at right angles to the diameter passing through the hinge and governor, with the pair of driving lips 15 extending downwardly, these also being preferably formed in the initial stamping.

I provide the helicopter with a parachute 16 having shroud lines 17 converging to a point 18 and from thence to a swivel 19 which is attached to some point on the inner wall of the chamber 20 formed by the cover and the cup, but preferably to the cover, so that when the parachute is filled and the cover opened, the suspension point will be away from the axis of the rotor, as shown in Figure 3. The parachute is designed of such material, preferably light parachute silk, that it may be folded and stowed within chamber 20 in such a manner that the cover may be closed thereupon and the locking lug 12 and the locking lip 8 engaged. The rotor or helicopter portion of the device is then ready for flight.

A preferred form of driving mechanism is a hand operated device, although in this respect, I do not wish to be limited to hand operated mechanism for this purpose as it is quite possible to utilize a small high speed electric motor for the purpose and to attain even greater altitude than can be obtained by hand. However, as one of the main purposes of the invention is to create a device which can be used by all, the hand operated accelerator is preferable.

This comprises, therefore, a handle 20' provided with an axial bearing pin 21 upon which rotates a starting platform 22. The lower end of the starting platform is provided with a driving groove 23 preferably tapered in section so that the bottom of the groove is of relatively small diameter and also only slightly larger than a driving rope 24 which is fixed by a knot 25 in the bottom of the groove and provided at the far end with a knob 26. The starting platform is maintained on the bearing pin 21 by means of a pin head 27.

The starting platform is preferably dished on top to receive the contour of the cup 2 and is also provided with driving pins 28 which engage notches 29 in the driving lugs 15 which extend over the side of the driving platform 22. The governor arm is restrained by the side of the driving platform, when placed thereon, from moving inwardly and unlocking the cover. Thus, when the rotor is placed upon the platform, the cover will remain closed although if no physical restraint were to be put upon the governor arm, the cover would open due to the action of the hinge spring 14.

The operation of the device is relatively simple. After the rotor has been placed upon the driving platform and pins 28 engaged in the rotor notches, the platform is rotated so that the string 24 is wound in the groove 23. The handle

20' is then grasped firmly in the weaker hand and the knob 22 taken in the stronger hand. With the handle 20 maintained in substantially a vertical position, the handle 26 is given a strong sharp pull to unwind the string and rotate the starting platform together with the rotor to as high a speed as possible within the limits of the string length. The higher the speed obtained and the less the time taken to develop this speed, the greater will be the energy stored in the rotor, and when gravitational effect and inertia of the device has been overcome, the entire helicopter will rise rapidly into the air until the speed of rotation is insufficient to sustain level flight, when it will start to fall.

During the rotation on the platform, the governor arm 9 is being subjected to centrifugal force developed by that rotation and therefore when the rotor leaves the platform and the governor arm is pulled out free of the platform, this centrifugal force is sufficient to cause the governor bar to keep the cover securely locked in place as the centrifugal force develops tends to move the lower end of the governor arm outwardly. When the speed of rotation of the rotor drops to such a point where this centrifugal force is insufficient to maintain the cover lock against the action of the hinge spring, the cover will open and the parachute is free to leave the cavity chamber 20.

However, I desire to so coordinate the centrifugal response of the governor and the urge of the hinge spring 14 so that the cover will not open until the speed of rotation of the rotor has dropped below the point where the rotor may still rise, but to open after the rotor has reached the apex of its flight and has started to drop. The downward motion aids the parachute to open, and clear the rotor.

I have found that when this adjustment of the governor is made, the parachute opens quickly and there is no danger of the shroud lines fouling the propeller blades. However, as there remains in the rotor a considerable amount of energy and the rotor will still be spinning even after the parachute is open, I prefer to attach the parachute to the rotor away from the rotational axis so that as soon as the weight of the rotor is sustained by the parachute the rotor will wobble and quickly damp out rotation, thus allowing the device to return to earth without rotation and without further interference of the rotor with the parachute action.

No definite figures for the weight of the governor arm, its length nor the pressure of the spring can be given as all of these factors depend upon the size of the rotor, the effectiveness in flight thereof with respect to the speed of rotation and to various other factors inherent in the individual design of a particular model. I have found, however, that such an adjustment is easy for any one skilled in the art to obtain and when once obtained, it is not so critical but what the device can be made in quantity production without further research or adjustment of the individual machines.

While I have described my invention in a particular preferred embodiment, I do not wish to be limited to any particular form of either the driving mechanism nor the governor, variations of which structures will be apparent to those skilled in the art. For example, there are many ways in hinging the governor arm to the rotor. It is also not necessary for the governor arm to extend downwardly. It may be a spring-con-

trolled weight which will move radially and outwardly to lock the cover and radially and inwardly to unlock it. It is also possible to perforate the bottom of the cup and eliminate the hinge spring entirely, relying on air pressure to open the cover and push out the parachute.

I also may desire to provide a lug opposite the governor arm of substantially the same size and shape in order to balance the rotor and provide recesses in the driving platform to receive both the governor arm and the lug, thereby rotating the propeller without additional means. The recess walls will prevent the governor arm from moving to unlock the cover, and will center the rotor on the platform.

The main feature of my invention, therefore, is the use of a centrifugal governor operable during flight to release the parachute at a predetermined point and which can be mechanically or physically locked during the application of power to the rotor to cause the flight until such time as a sufficient centrifugal force is developed to maintain the lock.

I claim:

25 1. A helicopter comprising a propeller, a casing

carried by said propeller, a parachute in said casing and attached thereto, and means actuatable under the influence of centrifugal force for opening said casing to release said parachute.

2. In a helicopter comprising a propeller 5 adapted to rise when rotated and to release a parachute at a point in its flight where said propeller is still rotating, swivel means attaching said parachute to said propeller away from the rotational axis thereof whereby the off-center 10 force applied by said parachute dampens rotational forces remaining in said propeller.

3. In combination with an impulse driven helicopter propeller and a releasable parachute carried thereby, means operable by the centrifugal 15 force developed by said rotor to release said parachute after said propeller has started descent.

4. The method of releasing a parachute from a chamber in an impulse driven helicopter which comprises locking said chamber, mechanically 20 maintaining said lock during initial rotation until centrifugal force is developed to maintain the lock, and regulating the locking forces to release the parachute shortly after descent begins.
